BATTERYLESS FLASHLIGHT

Joseph C. Clark, Merchantville, N. J., assignor to
 Jeny Corporation, Merchantville, N. J., a corporation of New Jersey

Application February 14, 1948, Serial No. 8,417

10 Claims. (CL. 171—76)

1

This invention relates to batteryless flashlights.

In recognition of the unpredictable life and unexpected failures of battery-powered flashlights, with their chemical characteristics and inevitable deterioration, many efforts have been exerted hitherto toward the creation of flashlights having manual generators or power plants, by which in any kind of emergency a source of light would be continuously available, because not subject to the deterioration found of the battery-powered devices. As previously developed, however, all prior art devices so far as known were characterized by undue size and weight, low power, frictional resistance to actuation, have been cumbersome and unwieldy, have not been capable of operation by mere pressure of a thumb, and in most cases provided inadequate light. Generally the arrangements of such devices were such as to reduce the visual acuity of the user of the device by causing the generated light to be inherently in the line of vision of the operator.

It is among the objects of the invention: to obviate the disadvantages of prior art devices; to provide a portable flashlight of such small size and weight as to be readily carried in a vest pocket or in a lady's purse; to simplify the structure and cheapen the costs of production of batteryless flashlights; to provide in gearing a novel unidirectional drive including overrunning in one direction without the use of a clutch; to utilize in a manual generator set the magnetic flux of the generator as the means for causing gears to mesh in one direction of running; to provide improvements in gearing having a reversing actuation while having an unidirectional ultimate drive; to provide a small compact manual generator system for a resistance unit energization, whether the unit be for illumination or for heat; to provide a batteryless flashlight with a substantially constant beam; to provide a batteryless flashlight with a light source so disposed relative to the housing that in the normal use of the flashlight the direct rays of the light source are shielded from the eyes of the observer by the housing of the device; to provide a batteryless flashlight formed of a reduced number of parts over prior art devices; to provide a batteryless flashlight of extremely thin and compact size in which the operations of assembly are quicker and simpler than in prior art devices and thus to reduce the costs of such flashlight; to provide a housing having suitable recesses for confining the operating mechanism

2

so that no screws are necessary to attach one to the other; to provide a housing of complementary halves which are cemented together to both retain the inner mechanism and to retain each other without the use of screws, rivets, mold inserts, etc.; to provide a flashlight having operating lever or button which can be latched in inoperative position by a slight additional pressure and sliding motion; and to provide other advantages as will become apparent as the description proceeds.

In the accompanying drawings forming part of this description:

Fig. 1 represents a perspective of an illustrative embodiment of the invention;

Fig. 2 represents a side elevation of the device of Fig. 1 with one substantial half portion of the two-piece case removed to show the operating portions and indicating the line of sight passing over the top of the device in the normal utilization thereof for illuminating purposes;

Fig. 3 represents a transverse vertical section through the complete housed assembly taken on line 3—3 of Fig. 2;

Fig. 4 represents an exploded perspective of certain of the elements for association in a riveted assembly, with some of the parts broken away or omitted, as the separately formed basic structural elements of the generator;

Fig. 5 represents a transverse lateral section through the case;

Fig. 6 represents a fragmentary side elevation of the operating generator assembly of the invention removed from the case, and with the large driving gear removed;

Fig. 7 represents a fragmentary transverse section through the laminated core of the generator system, showing the complementary housing elements operatively associated therewith, and the mounting of the rack bar guide;

Fig. 8 represents a fragmentary perspective of the central small pinion gear of magnetizable material, in its juxtaposition of the edge of the fly-wheel magnet used in the generator system, in the field of flux of such fly-wheel so as to magnetize such central pinion;

Fig. 9 represents a side elevation of the magnetized central gear with lines of force shown by arrows diagrammatically establishing a field of flux relative thereof, and as suggested by the arrows, attracting toward it the instantaneously out-of-mesh rack-driven slideable pinion gear of the generator system;

Fig. 10 represents in fragmentary side eleva-

tion the meshed relation of the magnetized central gear and the rack-driven pinion gear, and the meshed relation of the magnetized central gear coupled larger gear with the pinion, keyed to the fly-wheel magnet, as the rack moves inwardly to impart torque to the fly-wheel, with arrows indicating the relative instantaneous directions of motion of the respective parts;

Fig. 11 represents a fragmentary side elevation of the same parts as are shown in Fig. 10, with the rack-driven gear in the out-of-mesh position relative to the central magnetized gear to which it is forced by torque from the wheel, as the rack returns to its operative extended position because of its spring bias, to secure the unidirectional motion of the fly-wheel with the instantaneous direction of motions of the parts indicated by arrows;

Fig. 12 represents a fragmentary side elevation of the outer notched or recessed end of the rack bar, and the adjacent latch portions of the frame relative to which by the upward thrust indicated by the arrow the notch and latch become interlocked;

Fig. 13 represents a fragmentary side elevation similar to that of Fig. 12, in which the rack bar is indicated as moving outwardly under its bias, after being pushed downwardly out of the restrained interlocked position of latch and recess shown;

Fig. 14 represents a fragmentary side elevation of the rack bar and the notched frame element, with the resilient stop against which in the normal linear actuation of the rack bar the end of the rack abuts, as shown in full lines, and from which, under excessive linear push, the resilient device is caused to yield to permit interlocking of the rack and the frame elements, as indicated in dotted lines.

For simplicity of explanation, the dimensional terms used will be considered as applied to the device in the upright position indicated.

The operating portion of the apparatus is the complete generator system, arranged for anchored disposition in the housing or casing. The generator assembly in its entirety will, therefore, be described first, and the simplicity and ease of assembly thereof and of the generator with the case will become apparent as the relation of the parts is described.

The generator system or magneto of the device comprises a plurality of laminations 10, arranged in stacks as cores or core elements, and comprising complemental oppositely directed left and right cores 11 and 12 respectively. Each core comprises a plurality of identical stamped laminations and in stacked relation forming a generally vertical main body portion 13, shaped at the lower end in the arcuate fly-wheel partially enclosing or housing surface 14, and cut back above this by the upwardly sweeping arcuate surfaces 15, leading vertically into the relatively short transverse horizontal leg 16, spaced from the arcuate surface 15 to provide an operating clearance 17. The respective lamination stacks 11 and 12 are disposed in mutually reversed and confronting juxtaposed relation out of direct physical contact with each other so as to form the clearances shown. It will be apparent that the stamping of a plurality of identical laminations will be an economical procedure, as will the arrangement thereof in complemental core stacks. Preferably, each core has a pair of rivet openings 19. The stacks are held initially in proper operative mutual relation by axially in-

serting the free ends of the respective horizontal or transverse legs 16, of the complemental pair of stacks into the common hollow coil 18. The coil has two leads therefrom, respectively 20 and 21, which in due course are connected to the operative points of a screw threaded or other socket receptacle 23, or, if desired, directly to the resistance unit, to be described.

With the properly associated pair of stacks of laminations provided as just described, there are also provided a pair of shards or lateral frame members to be associated therewith, in the form of suitable stampings, respectively 25 and 26, of suitable non-magnetic material, for the opposite sides of the respective stacks. The frame member or shard 25, comprises a plate portion 27, having a pair of rivet openings 28-28 for alignment with the respective core rivet openings 19-19, defining a lower annular opening 30 and a transverse web 31, struck out of the plane of the plate 27. The web 31 contains a bushing or bearing opening 32. At the upper end the plate 27 is centrally cut and stamped to remove a portion, while integral tongues are formed at the top 25 of the plate and bent to form two ears 33 and 34, respectively, in substantial parallelism normal to plate 27 extending oppositely to the direction of stamped misalignment of the web 31. The ears have a pair of generally centrally located aligned apertures 35 and 36, respectively, through which, prior to association with the remainder of the assembly, the guide rod 37 is axially slid to relatively loosely mounted disposition therein, and the compression spring 38 is slid axially over the rod during the assembly of the rod with the ears. The length of the rod or shaft 37 and the disposition of the ears 33 and 34 is such that when the plate 27 is pushed against one side of the complemental stacks of laminations, the ears pass beneath the angular extensions in substantial lateral engagement with the contiguous surfaces of the laminations below the extensions 16, so that the shaft or rod 37 substantially abuts the inner surfaces of the laminations and is held against axial shift in the ears 33 and 34.

The complemental frame member or shard 26 comprises a plate portion 40, arranged to overlie the opposite surface of the complemental stacks of laminations from shard 25, with the upper edge of the plate cut down, as in the horizontal edge 41, so as to underlie the coil 18, but with a leg extension extending vertically above the edge 41, as indicated at 42, to extend behind the coil, axially thereof. The leg 42 and the plate 40 are each provided with lances or tongues 43 and 44, by which a resilient stop element, such as piano wire 45, or the like spring element, can be tightly held so as to furnish a vertically extending resilient stop disposed in a plane closely adjacent to the plane of the plate 40. A horizontal slot 46 is provided in plate 40 parallel to the upper edge 41 thereof, the median longitudinal axis of which passes across the line of the wire 45, between the upper and lower lances or tongues holding the wire, for a purpose to be discussed.

The plate portion 40 at the lower end has an annular opening 47, bridged by the transverse web 48, also struck out transversely of the plane of the plate, and which is provided with a bearing or bushing opening 50. Close to the upper edge of the lower annular opening 47 the plate 40 is provided with a pinion-bearing opening 51 to receive a shaft to be described. To one side of a vertical line passing through the bearing

opening 51 is the horizontal slot 52 generally parallel to the slot 46. At the side edge of the plate horizontally substantially opposite to the leg extension 42, the plate 40 is struck out to form at the top a combined guide and latch detent element 53, and the lower guide flange 54. The latch detent and the guide flange define between them a horizontal slot 55 of predetermined height to slidably receive a sliding rack bar member to be described. The plate 40 has rivet apertures 56—56 for aligned registration with the respective rivet apertures of the core and other plate. Usually prior to the assembly with the field core laminations, the housing wall portion or shard 26 is provided with the sliding rack bar 57, slidably mounted in the guide path 55 and laterally overlying the elongated guide slot 46. Rivets 59 complete the basic assembly. Rack bar 57 has at one inner free end a preferably slightly rounded end edge 58, arranged to abut and be stopped by the wire 45, in the inner retracted position of the rack bar. The rack bar 57 has teeth 60 along its lower edge, and a latch recess 61 of such size and disposition as latchingly to relatively receive latch 53 on its upper edge close to the thumb piece or handle 62 of the rack bar. The thumb piece may be a separately formed or molded element, but for economy may comprise a bent lateral extension of the rack bar as illustrated. Preferably, the thumb piece and housing to be described are complementally externally serrated to reduce slippage. The location of the latch recess 61 relative to the abutting free end 58 is such that when the rack is pushed inwardly until stopped the free end 58 engages and abuts against the wire 45 before the recess 61 becomes vertically aligned with the detent or latch 53, so that an affirmative push beyond normal operating pressure is necessary to actually bend or deflect the wire 45, before the detent 53 and the latch recess 61 become vertically aligned so that an upward push on the thumb piece will interengage the latch and recess to hold the rack bar in its inward position against the bias to be described, with the thumb piece close to the assembly so as to lie close to the edge of the housing to be described. The rack bar 57 carries a transversely extending yoke 63, the legs of which straddle the guide bar 37 and form a traveling abutment for one end of the compression spring 38, and the shank 64 of the yoke extends laterally through the rack bar to peined or riveted relation thereto in an aperture provided for the purpose as indicated at 65. The shank 64 of the yoke slides in the horizontal slot to act as a supplemental guide for the rack bar additive to the guide formed at the side edge of the frame member by the latch 53 and guide 54. A rack actuated pinion gear 66 of magnetic material such as steel or the like is press-fitted to the shank of a rivet or the like 67 passing through the short slot 52 in permanent mesh with the teeth 60 of the rack bar but oscillatable about such teeth as pivots in sliding longitudinally of the slot between a position in mesh with the gear 74 and a position out of mesh therewith.

A fly-wheel magnet 70 is provided as a solid disc of magnetized steel preferably of "Alnico" or the like, having at least two poles, and more if found desirable, having a transverse axle 71 and arranged in the assembly of the metal shards with the laminated stacks to pass through the aligned axle openings 32 and 50 of the respective webs, for rotation within the magnet annular openings 30, 14—14, and 47, formed respectively

in the first end plate, the laminated cores, and the other end plate. After assembly, the axle 71 protruding through side web 48 receives a pinion gear 72 with which it has a pressed fit. The mechanical train is completed by a shaft 73 upon which a pinion gear 74, of magnetizable metal such as steel or the like, is pressed immediately adjacent to and coaxial with a large driving gear 75, also pressed or otherwise keyed to the shaft 73, with the teeth of the large gear in constant mesh with the pinion 72. The center of the large gear 75 contains preferably a small steel ball 79 as a bearing engagement against the case, to be described. Large gear 75, shaft 73, magnetizable gear 74, and the ball bearing 79 are dropped into bearing opening 51 after the assembly is completed. When the case is applied it holds the large gear in place.

It will be observed that the teeth of the magnetizable pinion gear 74 overlie and are closely adjacent to the periphery of the fly-wheel magnet 70 so as to be constantly in the most intense field of flux of said magnet 70 and therefore in a constant state of magnetization having its own field, within the sphere of flux activity of which and of the fly wheel also the movable gear 66 is constantly disposed to be drawn toward the gear 74, with mutual attraction between gears 74 and 66. As gear 74 is relatively fixed and gear 66 is relatively movable in its slot in translation, the mutual attraction urges gear 66 toward meshing with gear 74.

A two-part casing or housing is provided, of which the parts are complemental and comprise one side wall 76 of generally oval shape, except at the top, in which it rises into a forwardly presenting semi-cylindrical socket-receiving set back or staggered element 77, and is generally arcuate or curvilinear at the lower end, and at the sides comprises the outer generally substantially parallel surfaces 78 and all of these walls terminate in a planar surface 83 parallel to wall 76. The inner parallel side wall edges 80 have a shoulder formation with the aligned short surfaces 81, parallel to the plane of the edge surface 83. The spacing of the internally presenting surfaces 80 is predeterminedly such that the assembly of mechanical and metal parts as described can be forced into the housing with a frictional engagement between the lateral side edges of the assembly and wall surfaces 80 of the housing, to furnish a tight engagement without rivets or other fastening aids or the like. The complemental housing is generally similarly shaped except for the formation of a lateral recess 82 in one side wall to receive and permit the sliding movement of the rack bar 57. The housing portions are formed in assembly with complemental opposing faces 83, between which, in completing the assembly, suitable adhesives are placed to glue the components together, enclosing the operative apparatus. In this connection it will be understood that as the two halves of the housing are brought into confronting juxtaposition for sealed contact, two gobs of plaster of Paris or the like, as indicated at 84 and 85, will be disposed on opposite sides of the socket receptacle 23 or of the actual resistance unit itself if used without a socket, in order to anchor it rigidly in the cylindrical housing extension, to prevent motion of the socket relative to the housing, and the more readily to permit the insertion and removal of the actuated resistance unit for the assembly. As shown, the resistance unit is a light bulb, but it will be clear that any other

resistance unit, such as a heating element for lighting cigarettes and the like may be substituted therefor.

In operation, with the device grasped in one hand, with the hand substantially at shoulder height, the fingers engage the remote edge of the device which has preferably serrations 66 to facilitate the grip, while the thumb engages the thumb piece 62, which may be similarly serrated as shown at 87. By contracting pressure the rack bar is pushed inwardly against the bias of the wire 45, until the latch recess 61 on the rack bar can be relatively withdrawn vertically from the latch detent 53, when in response to the bias of the compression spring after releasing thumb pressure the rack bar is extended to its fullest extent. This motion is permitted because the withdrawing rack bar, through its teeth, rotates the rack-actuated pinion 66, which is forced out of mesh with the magnetic pinion 74, against the resistance of the magnetic attraction between gears 74 and 66. As soon as the rack bar extends to its fullest extension, the unmoving pressure on the gear 66 is withdrawn or terminated and the latter is free to move in its slot 52 back into mesh with the gear 74, as soon as the respective teeth thereof are relatively out of interfering alignment. When the thumb is used to push the thumb piece inwardly of the housing, the pinions 74 and 66 are in driving meshing relation at the start of the motion, owing to the immediate rotation of gear 66 with start of the movement and instantaneous meshing as soon as the gear is so moved as to permit actual mesh. A smart accelerating push on the rack bar, as shown in Fig. 10, in the direction of the arrow, imparts a counterclockwise rotation to gear 66, and, thus, through meshing interengagement a clockwise rotation to the pinion 74, and, thus, therefore to the integral or keyed large gear 75. The large gear, being in permanent mesh with the fly-wheel magnet pinion gear 72 causes the fly-wheel magnet to be driven counterclockwise. The magneto action of the rotating magnet and the laminated core develops a voltage across the terminals of the resistance element, to heat it in the case of a mere resistor, or to render it incandescent in the case of a light source operatively mounted in the socket 23. The drive is overrunning because as soon as the rack bar, in the normal generating functioning of the device, abuts the wire 45, it stops without appreciable flexing of the latter and thus without permitting the latch recess and the latch to become vertically aligned, while the fly-wheel through its inertia continues to run in the clockwise direction. As the pinion 66 has stopped rotation with the stoppage of the linear thrust of rack bar, the inertia of the fly-wheel keeps the fly-wheel pinion 72 rotating counterclockwise, the meshed large gear 75 and keyed pinion gear 74 keep rotating clockwise, and the pinion 74 rotates against the slideable gear 66, which is free to respond to the pressure to move out of mesh by sliding along the slot, as it turns about a tooth in mesh with the rack bar. This forced unmoving of the movable gear 66 from the fixed magnetic pinion 74 is also secured by the spring pressed return outward movement of the rack bar in its permanent mesh with the gear 66. It will be seen that any rotation imparted by the fly-wheel to pinion 74 unmoves the movable gear 66 therefrom, whether the rack bar is stationary or sliding linearly, and this is against the attraction of the magnetized gear 74 for the

sliding gear 66. On the other hand, any drive imparted by the sliding rack bar is accompanied by automatic meshing to establish a rack bar drive of the fly-wheel in the same one direction.

- 5 The arrangement shown is therefore a complete overrunning clutch, without any of the conventional clutch structure, and without the weight, size, and susceptibility to wear possessed of such clutches.
- 10 The small and compact size of the generator unit, and the freedom from wear and the cheapness and sturdiness of the device will be evident. Having thus described my invention I claim:
  1. A hand operated portable generator for resistance units comprising a stator core, a coil embracing a portion of the stator core, a magnetized flywheel disc forming the armature of the generator, means mounting the flywheel for rotation, manually operated means biased in one direction arranged for bidirectional movement, gearing operatively associating the manually operated means and the flywheel for unidirectional movements of the latter and comprising a rack on said manually operated means, a bodily fixed gear in driving relation to said flywheel, a bodily movable gear biased toward the bodily fixed gear, means guiding said bodily movable gear for translational movement between positions respectively of meshing and unmoving relation between the gears while constantly maintaining meshing engagement between the bodily movable gear and said rack, said meshing relation between said gears being automatically effected upon movement of said manual means in one direction and said unmoving relation being effected against the bias upon movement of said manual means in the other direction and also as a result of torque from the bodily fixed gear in the inertial running of the flywheel.
  - 40 2. A hand operated portable generator comprising a plurality of laminations forming a flywheel opening and a coil opening, a magnet flywheel forming the armature of the generator, means mounting the flywheel for rotation in the said flywheel opening, a coil substantially embracing portions of said laminations and disposed in part in said coil opening, and means including a free wheeling assembly for securing unidirectional motion of the flywheel, said means including a pinion gear of magnetizable material juxtaposed to said magnet flywheel to be magnetically energized thereby, a bodily movable gear of magnetizable material juxtaposed to said pinion gear, and means for guiding said bodily movable gear for translational as well as rotative movements relative to said pinion gear with an urge toward said pinion gear through mutual magnetic attraction between said gears.
  - 60 3. A portable generator comprising a core, a coil embracing portions of the core, a plate mounted on the side of the core, a spring device, a guide and a detent formed on the plate, a push rod guided slidably in the guide, the push rod having teeth on the lower edge and having a detent recess in the upper surface thereof, means for biasing the push rod for extension from and relative to the plate, means on the push rod for pressing the rod inwardly against the bias to engage said spring device as a stop in the normal reciprocations of the push rod, said detent recess being so spaced in the push rod as to be out of registration with the detent but arranged so that an abnormal push causes deflection of the spring device sufficient to permit the detent to enter the detent recess, said spring device comprising a

resilient strip of metal in alignment with and traversing said push rod, and means for anchoring said strip toward both ends on opposite sides of said push rod to cause symmetry of resistance against said push rod and retain linearity of movement thereof.

4. A portable generator comprising a frame, a push rod slidably relative to the frame, means for guiding the push rod in its sliding movement, spring means biasing the push rod outwardly relative to the frame, a detent recess being formed in said push rod, a detent formed on the frame, a spring device against which the push rod abuts yieldable under excessive pressure to permit the detent to enter said detent recess but so arranged as to be incapable of yielding sufficiently under normal abutting pressures incident to push rod actuation as to permit the detent to enter said recess, said spring device comprising a resilient strip of metal in alignment with and traversing said push rod, and means for anchoring said strip toward both ends on opposite sides of said push rod to cause symmetry of resistance against said push rod and retain linearity of movement thereof.

5. A portable generator comprising a pair of parallel spaced plates, a flywheel magnet forming the armature of the generator, means on the respective plates journaling said flywheel magnet for rotation, an electro-magnetic core disposed between and spacing the plates, said core being so shaped as to have a coil recess toward one end and a flywheel recess toward the other end in which latter said flywheel magnet is rotatable, guide ears on one plate extending into the coil recess toward the other plate, a shaft mounted in the ears and disposed in the coil recess, a spring embracing said shaft, guide means on said other plate, a push rod slidably guided in the guide means, externally of said other plate, said guide means including a slot, a yoke mounted on the rod and extending through said slot and having fingers straddling said shaft abutting one end of said spring, a finger element on said rod for pushing it in one direction against the resistance of said spring whereby energy is stored for moving the rod in the other direction when pressure on the finger-piece is released, gearing connecting the rod with the flywheel for driving same in one direction, a coil electromagnetically associated with said core, a terminal mounting for a resistance unit electrically coupled to said core.

6. A portable generator comprising a rigid frame comprising a core and side frame members mounted on the lateral surfaces of the core, said core having a flywheel clearance, said frame members comprising web elements extending across the flywheel clearance and forming bearings for a flywheel, a flywheel magnet journalled in said bearings and rotatable in the said clearance, said magnet forming the armature of the generator a coil operatively associated with the core for generating a voltage as the flywheel rotates, a rack element, means guiding the rack element for movements relative to the rigid frame, a spring biasing the rack element toward one position, means for moving the rack element to another position against the bias by manual manipulation, a magnetizable gear in mesh with the rack element, means mounting the gear for translational movements substantially in a plane radial of the gear in a path generally parallel to the line of movement of said rack element while retaining the mesh with said rack element, and

a rotatable magnetizable meshing element in driven relation to said flywheel fixed against translation and disposed in the flux field of said armature to attract said gear magnetically to establish a drive for said meshing element from said rack element.

7. A portable generator comprising driving and driven members said driven member comprising a rotatable flywheel magnet forming the armature of the generator, an electro-magnetic coil juxtaposed to the magnet and comprising with the magnet a generator, said driving member comprising a rack having teeth, a gear train connecting the members, two contiguous elements of the gear train being formed of magnetic material of which at least one is juxtaposed to the flywheel magnet so as to be energized by the flux field thereof, means mounting the elements for relative bodily movement to permit them relatively to respond to magnetic attraction to move into driving interengagement and to move relatively out of said driving interengagement, said rotatable flywheel magnet in rotation developing tooth pressure on one of said elements to cause relative unmeshing separation of the elements to disconnect the driving and driven members to secure unidirectional movement of said flywheel magnet.

8. A portable generator comprising a core, said core so shaped as to form a flywheel clearance and a spaced secondary clearance, a flywheel mounted for rotation in the flywheel clearance, and comprising the armature of the generator, a plate mounted on the core and straddling said secondary clearance, said plate having a shaft bearing opening, a rack bar, means guiding the rack bar for motion relative to said plate, a shaft, a pinion and gear mounted on the shaft in coaxial relation and said shaft being arranged for mounting in said bearing in said plate to extend partially into said secondary clearance, antifriction means disposed in alignment with said shaft adjacent to said gear and so arranged that said housing abuts said antifriction device to maintain said shaft in its properly aligned position in said bearing, means for transmitting torque to said pinion from said rack bar, and a pinion coaxial with said flywheel in mesh with said gear when said housing abuts said antifriction device.

9. A hand operated portable generator for resistance units comprising a stator core, a coil in inductive relation to said core, a magnetized flywheel disc forming the armature of the generator, means mounting the flywheel for rotation, manually operated means biased in one direction and arranged for bidirectional movement, gearing operatively associating the manually operated means and the flywheel for unidirectional movements of the latter and comprising a rack operatively connected to the manually operated means and disposed for linear movement longitudinally of the rack, means guiding said rack for movement in a linear path, a bodily fixed gear in driving relation to said flywheel, a bodily movable gear, the axes of said gears being in general transverse alignment parallel to said linear path, means guiding said bodily movable gear for linear translational movement parallel to the linear path of said rack between a position meshing with said bodily fixed gear during thrust of the rack toward said gears, and a position unmeshing said gears during opposite retraction of said rack and also during the existence of and in response to ponderating torque from the bodily fixed gear

over that of the bodily movable gear incident to inertial running of said flywheel regardless of the state of motion of the rack.

10. A hand operated portable generator for resistance units comprising a stator core, a coil embracing a portion of the stator core, a magnetized flywheel disc forming the armature of the generator, means mounting the flywheel for rotation, manually operated means biased in one direction arranged for bidirectional movement, gearing operatively associating the manually operated means and the flywheel for unidirectional movements of the latter and comprising a rack on said manually operated means, a bodily fixed gear in driving relation to said flywheel, a bodily 15 movable gear biased toward the bodily fixed gear, means guiding said bodily movable gear for translational movement between positions respectively of meshing and unmeshing relation between the gears while constantly maintaining meshing engagement between the bodily movable gear and said rack, said meshing relation between said gears being automatically effected upon movement of said manual means in one direction and said unmeshing relation being effected against the bias upon movement of said manual means in the other direction and also as a result of torque from the bodily fixed gear in the inertial running of the flywheel, said respective gears being of magnetizable material and at least one of said gears being within the magnetic field of said armature so that the bias on the movable

gear is magnetic mutual attraction between both gears.
